UNITED STATES PATENT OFFICE

152,574

DESIGN FOR A HOLDER FOR PAPER SUNDAE DISH

Lawrence M. Turner, North Abington, Mass.

Application October 30, 1946, Serial No. 134,385

Term of patent 14 years

(Cl. D44—15)

To all whom it may concern:

Be it known that I, Lawrence M. Turner, a citizen of the United States, residing at North Abington, county of Plymouth, and Commonwealth of Massachusetts, have invented a new, original, and ornamental Design for a Holder for Paper Sundae Dish, of which the following is a specification, reference being had to the accompanying drawings, forming a part thereof.

In the accompanying drawings Fig. 1 is a plan view of a holder for a paper sundae dish showing my new design and Fig. 2 is an elevation thereof.

I claim:

The ornamental design for a holder for paper sundae dish, substantially as shown.

LAWRENCE M. TURNER.
